UNITED STATES PATENT OFFICE.

MORRIS SHEINMAN, OF NEW YORK, N. Y., ASSIGNOR, BY MESNE ASSIGNMENTS, TO
GIBRALTAR ALARM LOCK CO., INC., A CORPORATION OF NEW YORK.

AUTOMATIC ALARM-LOCK.

1,163,783.

Specification of Letters Patent. Patented Dec. 14, 1915.

Application filed June 1, 1914, Serial No. 842,131. Renewed May 20, 1915. Serial No. 29,451.

To all whom it may concern:

Be it known that I, MORRIS SHEINMAN, a citizen of the United States, and a resident of New York, county and State of New York, have invented certain new and useful Improvements in Automatic Alarm-Locks, of which the following is a full, clear, and exact description.

This invention relates more particularly to an automatic alarm such as disclosed in my Patent No. 1,097,884, dated May 26, 1914, in which an alarm is sounded in case a lock is tampered with.

In the patent referred to, the construction is such that the electric connection for the alarm was made through the main lock casing. This required wiring certain parts of the door and providing a connection in such a way that the door could be moved on its hinges without disturbing the electric circuit. This required considerable time in the installation of a lock of this kind and utilized more wire than was necessary and in addition was likely to be otherwise objectionable because of the wiring being applied to the door.

In the present invention the principal object is to overcome the objections referred to and so to construct a lock of the general character disclosed in my Patent No. 1,097,884 that the electric circuit with the alarm may be made through the keeper or other parts mounted on a fixed or stationary part, thus avoiding the necessity of any wiring whatever on the door and otherwise simplifying the construction so that an effective alarm is secured in case the lock is tampered with.

Another object of the invention is to provide a simple and efficient lock in which the bolt carries a movable contact member which is insulated from the bolt and so connected in an electric circuit which includes an alarm, that under the normal throw of the bolt the member is given a relative movement to keep the electric circuit open, but which in case the lock is tampered with by an effort to spread the lock and door from the jamb, the said member will be given a movement sufficient to close the circuit and sound the alarm and to continue ringing the alarm so long as the contact is made through said member.

A further object of the invention is to provide a simple and efficient automatic

alarm lock in which both contacts are normally mounted upon the lock proper, and in which an alarm connection is made through the keeper and means mounted thereon which coöperates with the lock.

A still further object of the invention is to provide a lock which is simple in construction and which may be readily made and assembled.

A still further object of the invention is to provide contacts for the alarm circuit which will keep the circuit closed by their movement together should the lock be tampered with.

With these and other objects in view, the invention will be hereinafter more particularly described with reference to the accompanying drawings, which form a part of this specification, and will then be pointed out in the claims at the end of the description.

In the drawings, Figure 1 is a detail rear elevation of the lock and keeper, the detachable casing member being partly broken away to show the interior working parts of the lock. Fig. 2 is a sectional plan view taken on the line II—II of Fig. 1 looking in the direction of the arrow and showing one form of electric circuit including a bell. Fig. 3 is a fragmentary perspective view showing the interior of a part of the lock and keeper. Fig. 4 is a fragmentary section of a part of the bolt of the lock taken on the line IV—IV of Fig. 5. Fig. 5 is a transverse section taken on the line V—V of Fig. 4. Fig. 6 is an elevation, partly broken away, showing a different form of contact member mounted on the lock casing, the circuit being broken. Fig. 7 is a view similar to Fig. 6 with the circuit closed and the keeper removed. Fig. 8 is a detail perspective view of the casing contact. Fig. 9 is a fragmentary section showing how the contact mounted in the bolt may bear against a metal lining or bushing instead of directly against the insulation. Fig. 10 is a transverse section taken on the line X—X of Fig. 9; and Fig. 11 is an elevation of the keeper, partly broken away, showing an insulated metal bushing or thimble for the adjusting screw.

The lock has a box-like casing 11 substantially rectangular in form and a cover member 12, the said cover member being secured to the box-like member 11 by screws 110.

13 and the box-like member being secured to the door 14 by screws or otherwise. A bolt 15 has an engaging part 16 at one end. This bolt is suitably guided in the casing member 11 and has its part 16 passing through an opening 17 in one end of the lock casing. The bolt has an enlarged skeleton part or body 17^a providing an opening or space 18 of irregular form, and said bolt is guided in the casing so as to be movable back and forth therein. This bolt has two projecting portions or lugs 19 and 20 forming a space between them and which are adapted to be engaged by a part 21 of a tumbler 22, said part 21 being normally located between said lugs. This tumbler is pivotally held to the bolt so as to move therewith and is normally forced to an engaging position by a spring 23, one end of which is held to the tumbler and its other end passed about a lug or projection 24 on said bolt. The tumbler has a shoulder 25 adapted to engage the casing lug 20 on one side thereof and with a shoulder 26 which is adapted to engage one edge or side of a lug 27 formed as a part of the casing member 11. It will be evident that if the tumbler is forced upward on its pivot so as to remove the shoulder 26 out of engagement with the lug 27, the bolt may be forced either forward or rearward as desired. This releasing of the tumbler and the forcing of the bolt to a locked or an unlocked position may be accomplished in any suitable way. As one means, a rotary member 28 is provided having arms 29 and 30 which are normally held in a horizontal position by a flat spring 31, one end of which is secured to the casing member 11 and its free end is adapted to rest against pins 31^a projecting from the arms 29 and 30. The rotary member 28 may be operated from the outside of the door by a key in any desired way and from the inside by a knob 32 or a key or both as preferred. By rotating the member 28 so as to cause the arm 30 to release the tumbler by engaging with the part 21 thereof, the bolt and tumbler may be moved to an unlocked position. If the member 28 is rotated by a key or the knob 32 in the opposite direction, the arm 29 will release the tumbler from engagement with the lug 27, thus forcing the tumbler and bolt to a locked position. During the unlocked position the cut-away part 33 of the tumbler will be forced to a position to engage the opposite sides of the fixed lug 27 so that the shoulder 34 by its engagement with said lug 27 will prevent the bolt being thrown to a locked position until the tumbler is released.

Any suitable means may be employed as an alarm or signal. As shown, a bell 35 is provided having one of its terminals connected to a wire 36 and the other terminal to a wire 37, forming a part of an electric

circuit 38, and included in this electric circuit is a battery 39 or other source of electric supply. The two terminals of the electric circuit are connected one to the keeper 40 and the other to an insulated bolt 41. 70 The keeper 40 is of any desired form and has a flange portion 42 to fit against the inner edge of the door jamb by screws or otherwise. This keeper has an opening 43 for the reception of the bolt engaging end 75 16 when the bolt is thrown to a locked position. The bolt or screw 41, which may be adjustable in the keeper 40, may be locked in its adjusted position by means of nuts 44, and said screw forms one terminal of the 80 electric circuit so that if the circuit is completed through the bolt 41 and the keeper 40, the alarm will be sounded.

To complete the circuit through the keeper and bolt 41, various means may be employed. As shown, the bolt engaging end 16 has an oval opening 45 therein in which is adapted to move a similarly shaped end 46 of a contact member 47. This contact member 47 is insulated from the bolt and from the lock member by means of a fiber or other bushing 48 which extends throughout the entire length of the engaging part 16 of the bolt. A further provision for insulating the contact member 47 from the bolt is a fiber or other washer 49 which insulates the pin 50 and prevents the same from coming into contact with the member 47 and yet serves to assist in guiding the contact member on the bolt. The contact member 100 47 is slotted, at 51, to span the insulating washer 49 and to permit the same to move relatively to the bolt lengthwise thereof and said member 47 is normally forced inward toward the screw 41 by a spring 52, 105 one end of which engages a part of the member 47, the other end of said spring engaging the insulating washer 49. The inner end of the contact member 47 is in the form of a rectangular bar or shank 53 and 110 is provided with a hooked end 54 which is adapted in a certain position and when ringing the alarm to engage the bent end 55 of a flexible wire contact 56. This contact 56 is secured at one end to the casing 115 cover 12 and its free end is located adjacent to the hooked end 54 of the contact member 47. During the locking and unlocking of the bolt, the member 47 moves with said bolt. If during the locking position the contact member 47 could be moved far enough inward to cause the hooked end 54 to engage the contact 55, the alarm would be sounded, but it is the intention of the invention that the bolt may be moved by a 120 key in the usual way to throw the bolt to a locked or unlocked position without ringing the alarm, and should the lock be tampered with, as by an attempt to spread the door from the jamb, in such case the alarm will 125 130

be sounded. This is accomplished by the coöperation of the contact member 47 with the adjustable screw or contact bolt 41 of the keeper. When the bolt is forced to a locked position, it will carry the contact member 47 and the outer end of the contact member will engage the head of the screw 41, thus forcing the member 47 against the tension of the spring 42 and holding the hooked end out of contact with the end 55 of the contact 56. If now a tool should be used to force the door by spreading the lock from the keeper, the spring 52 will force the contact member 47 to remain in contact with the screw 41 and until the hooked end 54 engages the end 55 of the contact 56 which will sound the alarm. The alarm will continue to sound so long as the spreading of the lock from the keeper takes place and the contact is made between the end 54 of the contact member 47 and the contact end 55. The contact 56 is in electrical connection with the casing 11 and the keeper and bolt are also in the electric circuit, so that the circuit when completed will be from the battery through the keeper, bolt, casing, contact 55, contact member 47, screw 41, bell 35 to the battery.

In Figs. 6 to 11 the construction is substantially the same as that already described except as to the form of the contact mounted upon the casing of the lock, the means for insulating the movable contact device mounted on the bolt, and the insulated bushing for the screw or bolt 41 forming one terminal of the alarm or signal circuit. The movable contact device 47 is the same as already described, and instead of having a sliding movement directly against the insulation, a metal thimble or bushing 57 is provided. This bushing 57, Figs. 9 and 10, is insulated from the locking end of the bolt 15 by the fiber 58 or otherwise, the said metal bushing 57 serving to form a better wearing surface for the end of the contact device 47 than might be obtained by having the insulation itself form the wearing surface. The inner hooked end 54 of the contact device 47 is adapted to engage the inwardly extending end 59 of a movable contact 60. This contact 60 is of a plate-like form and is pivoted at 61 to the casing member 12 in substantially the same position as the wire contact 56 and may be used in place of said contact 56. This contact 60 is normally forced in one direction by a spring 62, one end of which is held to the contact 60 and its other end passes about a pin or stud 63 carried by the casing member 12, the said contact 60 being limited in its movement in one direction by a shoulder or otherwise on said casing member 12. The purpose of pivoting the contact 60 is to give a greater range of movement than might be obtained by the wire contact 56 even when

the latter is flexible. This construction permits the contact end 54 on the contact device 47 to remain in engagement with the end 59 of the contact 60 for a considerable travel of said contact device 47 so that if the lock is tampered with, as in an effort to spread the lock from the keeper, even when such spreading is for a considerable distance, the alarm will be sounded or other signal made according to what is included in the electric circuit. The contacts 60 and 47 are so arranged and constructed that during the normal throw of the bolt by a key or by the knob 32 the screw 41 will cause the contact end 54 to be disengaged from the end 59 of the contact 60 as already explained and as shown in Fig. 6. Any spreading of the lock from the keeper will cause a relative movement of the contact 47 with the bolt 15, which will bring the end 54 into engagement with the end 59 of the contact 60. This will complete the circuit and cause the alarm to sound. As the spreading continues the contact 60 will move on its pivot against the tension of the spring 62 as shown in Fig. 7, and this condition will continue so long as the door remains spread from the keeper. It will thus be evident that it will be difficult to tamper with the lock without sounding the alarm and that by providing the movable contact 60, the circuit may be caused to remain closed for a considerable travel or movement of the device 47.

In Fig. 11, the keeper shown is substantially the same as that already described and differs only in providing a threaded metal bushing or thimble 64 for the engagement with the threaded end of the terminal screw 41. This provides a better engagement for the screw 41 and still provides means for insulating said screw from the keeper, the said metal thimble or bushing 64 being insulated from the keeper by a fiber or other socket 65.

From the foregoing it will be evident that simple and efficient means is provided whereby all wiring on the door for the electric circuit may be entirely dispensed with; that simple means is provided for insulating the contact device of the bolt; that simple means is provided whereby a better contact is provided between the contact device mounted on the bolt and the casing contact; and that said means as well as other parts of the lock are simple in construction and may be readily made and assembled.

Having thus described my invention, I claim as new and desire to secure by Letters Patent:—

1. In a lock, the combination of a casing, a bolt movable in said casing, a keeper, an adjustable member held in said keeper and insulated therefrom and arranged in the path of the bolt, a contact device bodily movable with the bolt and insulated therefrom and also movable lengthwise of the bolt and

adapted to engage the member in the keeper to force said device lengthwise of the bolt, a contact adapted to engage a part of the device in the absence of the member in the keeper, an electric alarm circuit including the keeper and the contact, and means for moving the bolt.

2. In a lock, the combination of a casing, a bolt movable in said casing, a keeper, a screw held in said keeper and insulated therefrom and arranged in the path of the bolt, a contact device carried by and insulated therefrom and bodily movable with the bolt and also movable lengthwise of the bolt and adapted to engage the screw in the keeper to force said contact device lengthwise of the bolt, a contact adapted to engage a part of the device in the absence of the member in the keeper, an electric alarm circuit including the keeper, the contact device and the contact, and means for moving the bolt.

3. In a lock, the combination of a casing, a bolt having an engaging part provided with an opening therethrough, an insulating bushing arranged in said opening, a keeper, a screw adjustably held in said keeper, means for moving the bolt, an alarm, an electric circuit including the alarm, a movable contact included in said circuit, a contact device having a body portion movable in the insulating bushing in the engaging part of the bolt so as to be insulated from said bolt, said contact being provided with an extended part having a finger adapted to engage the wire contact, and said contact device being adapted to move with the bolt and to be engaged by the screw to move the contact device relative to the bolt in one direction, a transverse insulated guide in said bolt, and a spring interposed between the guide and the end of the contact device tending normally to force the device in the opposite direction to close the circuit.

4. In a lock, the combination of a casing, a bolt having an engaging part provided with an oval opening therethrough, an insulating bushing arranged in said opening, a keeper, a screw adjustably held in said keeper and insulated therefrom, means for moving the bolt, an alarm, an electric circuit including the alarm, a contact included in said circuit, a contact device having an oval body portion movable in the insulating bushing in the engaging part of the bolt and provided with means adapted to engage the first-mentioned contact, said contact device being adapted to move with the bolt and to be engaged by the screw to move the contact device relative to the bolt in one direction, and means for forcing the device in the opposite direction to close the circuit.

5. In a lock, the combination of a casing, a bolt having an engaging part, a member arranged in the path of the bolt, means for

moving the bolt, a signal circuit, a contact in said circuit, a contact device also included in the circuit and slidingly held on the bolt and insulated therefrom and provided with an extended part having a finger adapted to engage the wire contact, said contact device being adapted to move with the bolt and to be engaged by the member to move the contact device relative to the bolt in one direction, and a spring tending normally to force the device in the opposite direction.

6. In a lock, the combination of a casing, a keeper, a screw in said keeper, a bolt having an engaging part provided with an opening therethrough, means for moving the bolt, an alarm, an electric circuit including the alarm, a contact included in said circuit, a contact device having a body portion movable in the opening in the engaging part of the bolt and insulated therefrom and provided with an extended part having a finger adapted to engage the wire contact, said contact device being adapted to move with the bolt and to be engaged by the screw to move the contact device relative to the bolt in one direction, and a spring tending normally to force the device in the opposite direction to close the circuit, said circuit being connected to the keeper and to the screw.

7. In a lock, the combination of a casing, a bolt having an engaging part provided with an opening therethrough, a keeper, a screw adjustably held in said keeper, means for moving the bolt, an alarm, an electric circuit including the alarm, a contact included in said circuit, and insulated means arranged in the opening in the engaging part and adapted to engage the screw and be forced thereby into engagement with the contact to complete the circuit.

8. In a lock, the combination of a casing, a bolt movable in said casing, a member arranged in the path of the bolt, a keeper adapted to be engaged by said bolt, a contact device bodily movable with the bolt and insulated therefrom and adapted to engage the member to force said contact device lengthwise of the bolt, a contact adapted to engage a part of the device, and signaling means controlled by said device.

9. In a lock, the combination of a casing, a bolt movable in said casing, a keeper, an adjustable member held in said keeper and insulated therefrom and arranged in the path of the bolt, a contact device bodily movable with the bolt and insulated therefrom and also movable lengthwise of the bolt and adapted to engage the member in the keeper to force said device lengthwise of the bolt, a pivotally held contact adapted to engage a part of the device in the absence of the member in the keeper, an electric alarm circuit including the keeper and the contact, and means for moving the bolt.

10. In a lock, the combination of a cas-

ing, a bolt movable in said casing, a keeper, a screw held in said keeper and insulated therefrom and arranged in the path of the bolt, a contact device carried by and insulated therefrom and bodily movable with the bolt and also movable lengthwise of the bolt and adapted to engage the screw in the keeper to force said contact device lengthwise of the bolt, a movable second contact adapted to engage a part of the device in the absence of the member in the keeper, an electric alarm circuit including the keeper, the contact device and the contact, and means for moving the bolt.

15 11. In a lock, the combination of a casing, a bolt having an engaging part provided with an opening therethrough, a keeper, a member held in said keeper, means for moving the bolt, an alarm, an electric circuit including the alarm, a contact included in said circuit, means arranged in the opening in the engaging part of the bolt and adapted to engage said member and be

20

forced thereby into engagement with the contact to complete the circuit, and an insulating metal bushing arranged in the bolt opening and forming a bearing for said means.

12. In a lock, the combination of a casing, a bolt movable in said casing, a screw arranged in the path of the bolt, a keeper adapted to be engaged by said bolt, a contact device bodily movable with the bolt and insulated therefrom and adapted to engage the screw to force said contact device lengthwise of the bolt, a contact adapted to engage a part of the device, signaling means controlled by said device, and an insulated and threaded bushing forming a support for the screw.

This specification signed and witnessed this 28th day of May, A. D. 1914.

MORRIS SHEINMAN.
